SHOE STRUCTURE

Harold L. Pierson, Sea Breeze, N. Y., assignor to
E. P. Reed & Co., Rochester, N. Y., a corpora-
tion of New York

Application December 22, 1949, Serial No. 134,459

3 Claims. (Cl. 36—17)

1

This invention relates to a shoe structure, with more particular reference to the general type of shoe, including an insole to which an upper is attached, and an outer sole attached to the upper and insole, and it has for its chief purpose to afford a sole construction that possesses greater flexibility, resiliency, uniformity and wearing qualities than heretofore possible in shoes of this character without increasing the cost of manufacture.

In shoes of this type, where an upper and welt are attached by conventional stitching processes to an insole, the recess formed by the attached portions of the upper and insole is usually filled with a plastic mass of ground cork or like material, spread over the recess with a suitable instrument to level off the plastic filler with the surrounding wall or attached portions of the upper and insole, after which the shoe is levelled and the outer sole attached in the conventional manner, and with shoes constructed in this fashion, the plastic mass between the inner and outer soles disintegrates and breaks down after a short time, spreading irregularly over the area within which it is confined and resulting in depressions and unevenness in the inner sole on which the foot rests, or bumps and hollows in the foot-engaging surface of the inner sole, leading to considerable discomfort, and it is a purpose of the invention to overcome this objection by eliminating the use of a plastic filler, which hardens after it is in place but subsequently disintegrates, and substituting for such plastic filler a filler blank cut from a sheet of highly compressed ground cork or other suitable resilient material combined with a latex cement or suitable rubber binder united under heavy pressure to produce a sheet of uniform thickness that will maintain its original surfaces and its resiliency indefinitely without breaking down or disintegrating, the filler blank being cut to fit the recess bounded by the attached portions of the upper and insole and located between the insole and outer sole.

Various attempts have been made to employ cut filler blanks in the described relationship but the results have been unsuccessful from a practical standpoint owing to the difficulty in cutting a blank to fit accurately within the recess and to the tendency of the insole to drop somewhat in relation to the filler blank in certain types of shoes characterized by a gutter in the insole immediately above the edge of the filler blank, and it is a further purpose of the invention to overcome the first of these obstacles by forming the

2

edge of the filler blank with peripheral recesses preferably in the form of V-shaped openings or otherwise, affording edge portions of reduced width or tapering which flex laterally and adjust themselves to the wall formed by the attached portions of the insole and upper, so that a cut filler of given size will fit satisfactorily in different sized shoes in which the recesses may vary slightly in size, making it unnecessary to cut the filler blank with an edge that fits exactly in the recess.

Another object of the invention is to support effectively the portion of the insole that overlies the gutter of the insole and the edge of the filler by placing within the gutter area of the insole a plastic filler that occupies the gutter and also fills the spaces between reduced or tapered edge portions of a cut filler when the latter is inserted in the recess and pressed against the insole, with the result that the cut filler and insole are characterized by uniformly smooth, continuous and uninterrupted surfaces extending completely between the sides of the insole at the ball portion of the shoe, so that there is no opportunity for irregularities or depressions forming in the insole after the shoe has been worn for a while, since the cut filler is supported so as to give a uniformly smooth, resilient surface completely under the insole between the sides thereof and will maintain its uniform thickness and resiliency indefinitely throughout the life of the shoe.

To these and other ends, the invention consists in the construction and arrangement of parts that will appear clearly from the following description when read in conjunction with the accompanying drawings, the novel features being pointed out in the claims following the specifications.

In the drawings:

Fig. 1 is a transverse vertical sectional view partially broken away, showing a welt-type of shoe constructed in accordance with a preferred embodiment of the invention, the section being taken through the widest portion of the filler blank;

Fig. 2 is an enlarged detail sectional view partially broken away, illustrating the upper, welt, and insole with its attaching portion, showing the position of the plastic filler before applying the cut filler blank;

Fig. 3 is a view similar to Fig. 2, showing the filler attached, the section being taken through one of the peripheral openings of the filler blank;

Fig. 4 is a view in elevation of the filler blank;

Fig. 5 is a view in elevation of the shoe after the inner sole, welt, upper and cut filler blank

are attached, showing the filler blank in position in the recess before attaching the outer sole, and

Fig. 6 is a detail sectional view of the insole showing the attaching flange or lip formed integral therewith.

The invention is applicable to any shoe where it is desirable to arrange a resilient, flexible filler between an insole and outer sole, and is shown applied to a welt-type of shoe in which a welt and upper are attached to a flange or lip cut from and formed integral with an insole, the cut filler blank being positioned in the recess surrounded and formed by the wall consisting of the attached portions of the insole flange, upper and welt.

Fig. 6 shows the insole used in the structure disclosed and preferably consisting of any light-weight, flexible material such as a curried leather split, or any comparatively soft, flexible leather, as indicated at 1, the insole being cut as indicated at 2 to provide a flange or lip 3 that is bent upwardly away from the body of the insole to afford an attaching portion to which the upper and welt are stitched in the usual manner.

In the structure shown, canvas strips 4 and 5 are suitably fastened on opposite sides of the flange or lip 3, being attached by cement to the adjacent surfaces of the flange 3 and the adjacent areas of the insole at the base of the flange to impart sufficient strength to the flange to permit of attaching the upper and welt while permitting the use of an extremely soft, flexible, light-weight insole. After the insole has been prepared with the flange or lip 3 projecting away from its one surface and provided on opposite sides with the canvas strips 4 and 5, the upper 6 and welt 7 are stitched to the flange 3 of the insole by the stitching 8, as usual in this type of construction, the assembled insole, upper and welt being disposed on a last during these operations, after which it is in condition to receive the filler blank and outer sole. The structure thus far described is conventional, and the invention forming the subject matter of this application has to do with the character and form of the filler blank and the manner in which it is attached to the insole.

With a shoe such as described, the formation of the flange or lip 3 in the insole and bending of the flange away from the insole results in a gutter or depression adjacent to and inwardly of the flange 3 at the base of the latter, see Figs. 2 and 6, and in order to prevent the insole from dropping at such point or the edge of a cut filler from moving into such gutter or depression, the gutter is first provided with a mass of plastic filler 9 of ground cork and adhesive that is applied into and above the gutter or depression at the base of the flange 3, so that when the cut filler blank is laid over and pressed against the insole, the inner surface of the filler blank will lie flat throughout its entire area and there is no tendency for the edge of the filler blank to bend into the gutter of the insole or permit an objectionable irregularity in the inner surface of the insole that results if the latter drops away toward the filler blank. Thus the insole can not break down at points overlying the gutter, which when filled with the plastic holds the insole in its proper position throughout and maintains a uniformly smooth and resilient surface entirely across the insole at the ball portion of the shoe.

The cut filler blank is shown in Fig. 4 and is preferably made from a sheet of sufficiently thick,

resilient, flexible material such as ground cork and latex, or other rubber or resilient composition that is fabricated under high pressure into sheet form, and cut to the desired shape to provide a cut filler blank which when placed in the shoe will maintain its uniform thickness throughout and smooth continuous surfaces indefinitely without possibility of the mass of which the filler is composed disintegrating or breaking down.

It is difficult and impractical to cut such a filler blank to fit accurately within the recesses of differently sized shoes, and in order to use a cut filler blank that can be properly and effectively fitted within shoes of different sizes within certain limits, the filler blank is cut to provide a series of peripherally arranged openings 10 which are preferably V-shaped, resulting in a multiplicity of reduced edge portions 11 at the edge of the blank, the projections 11 being preferably tapered and defined by converging sides, thus affording reduced edge portion on the filler blank which will readily flex or bend and adjust themselves laterally to the surrounding adjacent wall defining the recess in which the filler blank is positioned and formed by the attached portions of the upper and insole. By providing a sufficient body of plastic material 9 in the gutter at the base of the attaching flange on the insole, when the filler blank is positioned against the insole and pressed into contact therewith, the plastic material is squeezed into the recesses or V-shaped openings 10 between the tapered portions at the edge of the filler blank, thus substantially filling the recesses and enabling the filler blank to support the insole as completely and effectively as if the filler blank were cut to fit exactly within the recess in which it is fitted, with its edge conforming to the adjacent surrounding wall or attached portions of the upper and insole.

The cut filler blank may be temporarily attached to the insole during the subsequent operations on the shoe by spotting it with a cementing medium on the side toward the insole after which the shoe is levelled in the usual manner and the outer sole attached either by stitching to the welt or by cementing to the adjacent portions of the insole and upper.

It will be understood that any suitable material may be used for the cut filler blank as sponge rubber, rubber and cork combinations, or other compositions that lend themselves readily to being cut, or molded to a given shape under high pressure, and will maintain their original flexibility and resiliency throughout the life of a shoe, and the structure enables using such materials to produce a filler blank without requiring the blank to be cut to the exact size of the recess or cavity within which it is fitted, so that one size of blank can be employed for various sizes of shoes, while at the same time insuring complete support for the insole by the resilient filler blank throughout the width of the insole, and uniformly smooth and uninterrupted inner surfaces of the filler blank and insole entirely across the ball portion of the shoe. This construction entirely eliminates the possibility of bumps, depressions, or irregularities of any kind in the inner or foot-engaging surface of the shoe insole and insures a continuous and uniformly smooth, flexible and resilient surface supporting the insole throughout its width and consequent absence of possible discomfort to a foot resting on the insole.

While the invention has been described with reference to a particular construction, it is not

confined to the exact details herein disclosed, and this application is intended to cover such modifications or changes as may come within the purposes of the invention and the scope of the following claims.

I claim:

1. A shoe structure including a soft, flexible insole, an upper attached to the insole, an outer sole, a single-ply cut filler blank of resilient flexible material having uniform thickness throughout arranged between and contacting the insole and outer sole respectively and extending entirely across the recess bounded by the attached portions of the upper and insole, said filler blank having transverse peripheral openings affording spaced narrow laterally flexible edge portions arranged in juxtaposition to the wall formed by said attached portions of the upper and insole, said filler also having a uniformly smooth continuous and uninterrupted cushioning surface under the insole extending entirely across said recess at the ball portion of the shoe, and a plastic filling material occupying the spaces between said edge portions of the filler blank.

2. A shoe structure including a soft, flexible insole having an integral attaching flange cut therefrom providing a gutter in the insole adjacent to and inwardly of the attaching flange, an upper attached to said attaching flange of the insole, an outer sole, a single-ply cut filler blank of resilient flexible material having uniform thickness throughout arranged between and contacting the insole and outer sole respectively and extending entirely across the recess bounded by said attaching flange and the attached edge of the upper, said filler blank having transverse peripheral openings affording spaced narrow laterally flexible edge portions arranged in juxtaposition to the wall formed by said attached portions of the upper and insole, and a plastic filler arranged in said gutter between said narrow edge portions and the insole and in the transverse

peripheral openings between said edge portions, the cut filler also having a uniformly smooth continuous and uninterrupted cushioning surface under the insole extending entirely across the ball portion of the shoe.

3. A shoe structure including a soft, flexible insole having an integral attaching flange cut therefrom providing a gutter in the insole adjacent to and inwardly of the attaching flange, 10 an upper attached to said attaching flange of the insole, an outer sole, a single-ply cut filler blank of resilient flexible material arranged between and contacting the insole and outer sole respectively and extending entirely across the recess bounded by said attaching flange and the attached edge of the upper, said filler blank having transverse peripheral openings affording spaced narrow laterally flexible edge portions arranged in juxtaposition to the wall formed by 15 said attached portions of the insole and upper, and a filler arranged in said gutter between said narrow edge portions and the insole, said cut filler also having a uniformly smooth continuous and uninterrupted cushioning surface under the 20 insole extending entirely across the ball portion of the shoe.
